UNITED STATES PATENT OFFICE.

WILLIAM MORTIMER CLARK, OF BAYONNE, NEW JERSEY.

ACETYLENE-GAS GENERATOR.

SPECIFICATION forming part of Letters Patent No. 632,511, dated September 5, 1898.

Application filed October 11, 1898. Serial No. 693,202. (No model.)

To all whom it may concern:

Be it known that I, WILLIAM MORTIMER CLARK, a citizen of the United States, residing at Bayonne, in the county of Hudson, in the State of New Jersey, have invented a certain new and useful Improvement Relating to Acetylene Gas, of which the following is a specification.

My improvement applies to that class in which the apparatus contains a large quantity of water, with provisions for introducing the carbid thereto according as the gas is consumed.

My invention consists in certain novel features connected with the automatic feeding of the carbid to the generating-tank.

It also involves important improvements in the apparatus.

The accompanying drawings form a part of this specification and represent what I consider the best means of carrying out the invention.

Figure 1 is a vertical sectional elevation of an acetylene-gas generator embodying my improvements. Fig. 2 is a detached view showing in perspective the ribbed wheel, inclined plane, and certain contiguous parts relating to the carbid-feeding devices. Fig. 3 is a fragmentary view of a portion of the hopper side, illustrating the provisions for the introduction and removal of the carbid-feed wheel; and Fig. 4 is a detached view showing a transverse section through the loose and fast pulleys of the carbid-feeding devices and the tight and loose positions of the flexible band or strap carried by said loose pulley for intermittently overlapping and frictionally turning the fast pulley to effect the feed.

Similar letters of reference indicate corresponding parts in all the figures where they appear.

A is the main case, an upright cylindrical vessel of sheet metal having a bottom, but open at the top, and A' is a smaller casing mounted concentrically within, open both at the top and bottom. The annular space between the bottom of the casing A' and the main casing A is tightly stopped with a bottom A², which is a frustum of a cone.

A³ is a narrow casing extending up and

down on the exterior of the main casing A and having an inclined bottom A⁴, extending inward through an aperture a in the side of A, which performs important functions.

A suitable bell B is introduced, rising and sinking in the annular space provided between the casings A and A', which space is partially filled with water x to form a seal, so that this bell may serve the ordinary functions of a gas-holder, delivering the gas through a pipe C, which descends in the interior to a point below the lowest position of the bell and thence is led out through the casing A and supplies the gas to the burners. (Not shown.)

I provide means to be described farther on for supplying the carbid in instalments of about equal quantities. The frequency of the supply of these instalments of carbid is made to depend on the rate of consumption of the gas. If the carbid is prepared in a certain way, it will not generate the gas on its first introduction to the water, but only after it has been in the water for an interval of a second, more or less, after which interval the reaction between the water and the carbid will proceed, as usual, and generate the gas. These instalments of carbid are thrown down in the casing A² and are deflected inward by the inclined surface A⁴. By the time the water has overcome the defensive coating the grains of carbid of various sizes have descended and been thus deflected inward and allowed to sink. The gas being generated at that point and rising upward is certain not to move outward through the aperture a, but to rise up within the vessel and be accumulated under the bell B.

D is a cord or chain attached to the center of the top of the bell B and leading upward over a pulley (not shown) and laterally and obliquely away. At a point sufficiently beyond said pulley to allow sufficient chain for the extreme rising and sinking of the bell it is joined to a broad flexible band or strap D' of thin sheet-brass, which is coiled partly around a pulley G', fixed on a shaft G, supported in fixed bearings and carrying a peculiar longitudinally-ribbed feed-wheel G², which, equipped with fingers G³, receives and

measures the carbid. The latter is allowed to descend thereto on a movable inclined plane I, capable of vibrating up and down on the fixed center I'. To this tilting plane I 5 the carbid is liberally supplied from a hopper A⁵. The several ridges of this ribbed wheel are of triangular section, inclined as shown. I will call the several spaces between them "pockets." The movable incline I by 10 dropping into the several pockets g as they are presented serves as a pawl to prevent any backward turning of such wheel and also to lead the carbid along its inclined surface from the hopper A⁵ into the pockets g as they are 15 presented successively. The thin metallic strap D' takes hold of the fast pulley G' only frictionally by embracing it tightly when it is pulled by the descent of the bell B. When 20 the tension on this strap is relaxed by the rising of the bell, its elastic nature causes it to release its hold on the pulley G', so that it may be again wound upon such pulley without imparting any reverse motion thereto. This is effected by the aid of a loose pulley 25 H, mounted on the same shaft G and having a diameter nearly or quite equal to that of the fixed pulley G'. The end of the strap D' is riveted or otherwise permanently secured to the loose pulley. This loose pulley carries 30 a loaded lever H', the gravity of which tends to turn it in the direction to wind up the strap. When the strap D' is pulled and unwound, it not only turns the loose pulley and elevates the weighted lever H', but also takes 35 hold frictionally on the periphery of the fixed pulley G' and turns the latter, and thereby correspondingly turns the ribbed wheel G². Every movement of the bell B downward turns the shaft G, and consequently the ribbed 40 wheel, a corresponding portion of a revolution, and every ascent of the bell allows the strap D' to move idly around in the proper direction to take a fresh hold. The action differs from an ordinary pawl in the fact that 45 every movement of the bell downward, however small, results in a turning movement of the ribbed wheel, and every movement of the bell upward, however small, results in conditioning the parts for the next correspond- 50 ing movement.

A⁶ is a chamber leading obliquely downward from the hopper A⁵ into the outside casting A³. The ribbed wheel G² is inclosed loosely within this chamber A⁶. Each rising 55 movement of the bell B slackens the strap D' and allows the loose pulley H to be turned. Each descending movement of the bell results in turning the loose pulley H and also the fast pulley G' in the proper direction to give a forward motion to the ribbed wheel G², and consequently to transfer the carbid which is in the several pockets toward the delivery-point. It is desirable that the bell shall make approximately uniform movements upward and 60 downward sufficiently extensive to turn the ribbed wheel G² so much as will cause one or 65

more of the pockets g to empty at each descent. My construction promotes this; but it is not necessary to the success of my invention that the motion of the bell shall be large or uniform. When the bell makes very slight movements by reason of the supply of gas rising from the water differing but little and for only a brief period from the rate of consumption, the chain D, and consequently the strap 70 D', will move so little that the loose pulley H will turn but slightly, if at all; but with very ordinary skill in the construction and adjustment it is easy to insure larger movements by the intermittent conditions under which 75 the carbid is thrown into the water. The fingers G³ have an enlargement at the outer end of each like the head of a nail, which aid the pockets to receive and retain approximately uniform quantities of carbid and to discharge the contents of each pocket suddenly when the wheel G² has turned sufficiently to induce the latter step. The mode by which 80 these fingers contribute to the reception of the carbid will now be more fully explained. 85

The lower edge of the movable inclined plane I is equipped with deep notches i, arranged each to receive and allow the passage of a finger when it is presented thereto. The inclined position and the shaking of the plate I having induced an approximately uniform spreading of the loose material along its upper surface a movement downward a little at each of the jolting motions which it receives by the successive descents of the lower edge 90 is certain to present more or less of the carbid so near the edge that it will be ready to slide off, and it will fall into the pocket as the further slow revolution of the wheel G² presents more and more of the pocket to receive 95 it. While this condition obtains the rise of the next series of pins G³ through their respective notches i serves in a manner analogous to the teeth of a rake in moving forward the loose particles which are sufficiently near 100 the edge, leaving the more distant ones unaffected. These notches i are preferably so deep that the fingers will never touch the inclined plate I, leaving the lifting of the latter to be effected entirely by the ridges G⁴. When 105 thus proportioned, the sole functions of the fingers, which may be common nails carefully set in the correct positions, is to promote the reception of an approximately uniform quantity of the carbid when the pocket in advance 110 passes the receiving-point and to aid in retaining the carbid in the pocket behind it at the delivery period. My experiments indicate that it is easy to hold the small lumps and 115 loose particles of the carbid by these pockets, aided by the fingers, so that but little shall be scattered in advance and to discharge the whole when the pocket has attained a certain amount of inclination.

I maintain a gentle tension on the chain D 120 and strap D' by means of a slight weight D², attached to the chain in the position repre- 125

sented. In practice I prefer to so adjust the parts that the motion of the bell B shall usually be excessive, the irregularities being taken up by the varying amounts of slack in 5 the chain at certain periods between the weight D² and the bell.

To provide for the convenient introduction and removal of the ribbed wheel G² to and from the hopper A⁵, I make in one side of the 10 same a circular opening of a diameter adequate for the lateral introduction of the ribbed wheel. The external portion of the shaft G between the hopper and the pulleys G' H turns in a bearing-recess j' therefor in 15 a slot j in the plate J, which slides horizontally in upper and lower guideways A¹³ A¹⁴ on the side of the hopper, the closing movement of the plate being limited by a stop A¹⁵, while a perforation in the plate is arranged to register with a similar opening in the hopperside 20 when the parts are in position for receiving a fastening-pin P to positively retain the parts in position.

I provide for washing and filtering the gas. 25 Within the interior of the inner casing A' is a horizontal floor-plate A⁷, on which rests a few inches depth of water y, supplied through a pipe A⁸ from an elevated tank A⁹. K is a cock through which this water may be drained 30 off when required, and L is a cock by which the proper level may be determined in the filling.

A¹⁰ is a large bent pipe leading up through the floor-plate A⁷ and delivering the gas upward through a valve N below the level of the water y. The gas is produced at a sufficiently higher pressure than that at which it is required to be consumed, so that it can bubble up through this water and be washed. 35 A¹¹ is a higher floor-plate which need be only approximately tight. The aperture in the middle is covered by a series of sponges M, kept in place by a slight inclosing casing A¹². These sponges filter out all the solid 40 particles.

C is a safety-valve in a branch C², adapted to relieve the pipe C from pressure, if such should be engendered in the machine at any time. The pipe C² may deliver through the 45 roof of the building.

The upper edge of the casing A is deflected outward at one point to facilitate the introduction of the water x. The side of the outside case A³ is equipped with a funnel A¹³, 50 leading upward from an orifice to a point above the water-line, to allow the introduction of the water z, which fills the lower portion of the casing A and which by its chemical reaction with the successive instalments 55 of carbid produces the gas. I provide a liberal aperture a' with means for closing it, through which the more or less impure water z and any sediment may be discharged from the bottom of the casing at intervals.

65 I effect the preparation of the carbid by thoroughly coating it by dipping in a suitable

oil. I prefer the lubricating-oil produced by refining petroleum, which is known in the trade sometimes as "paraffin-oil," but more properly as "spindle-oil" No. 25. No 26 may 70 serve. I do not find that the result is materially affected by an excess; but I prefer that the carbid be drained of all its surplus oil before being placed in the hopper A⁵.

I claim as my invention—

1. In apparatus for the manufacture of acetylene gas, the combination with the main case A having a carbid-supply opening a, of the smaller inner casing A', open at both ends, a bottom A², closing the space between said case and casing, a horizontal partition within the casing A', having a seal A¹⁰, communicating at one end beneath said partition and discharging at the other above the same, a movable bell inclosing the casing A' and a suitable gas-discharge, substantially as herein specified.

2. In apparatus for the manufacture of acetylene gas, the combination with the main case A having a carbid-supply opening a, of the smaller inner casing A' open at both ends, a bottom A², closing the space between said case and casing, a lower horizontal partition within the casing having a seal A¹⁰, communicating at one end beneath said partition, and discharging at the other end above the same, an upper partition also within the casing having a filter-passage, a movable bell and a suitable gas-discharge, substantially as herein specified.

3. In apparatus for the manufacture of acetylene gas, the combination with the tank A, a bell operating within said tank as described, a carbid-hopper communicating with said tank and having a carbid-feed device, fast 105 and loose pulleys G', H, the latter operating the feed device a strap D' connected with the bell to be reciprocated by the movements thereof and connected to the loose pulley to only turn the fast pulley when traction is exerted on said strap, all arranged for joint operation substantially as herein specified.

4. In apparatus for the manufacture of acetylene gas, the combination with the tank A, a bell operating within said tank as described, 115 a hopper communicating with said tank and containing a ribbed wheel G², connections with the bell for intermittently rotating the wheel G², and movable incline I, also within the hopper supplying carbid to the wheel-pockets and acting as a pawl to prevent any retrograde movement, substantially as herein specified.

5. In apparatus for the manufacture of acetylene gas, the combination with the tank A, 125 the bell B, operating within said tank, the latter having the carbid-induction opening a, of the broad strap D' reciprocated thereby, the loose pulley H oscillated by such strap, the fast pulley G' turned step by step by the friction of the strap due to such reciprocations and a hopper communicating with the tank

and containing a device operated by the latter pulley for delivering carbid to the tank together with the outer casing A³, main casing A having the hole a, inner casing A' and 5 nular bottom A² and provisions for washing, filtering and conducting away the gas, all arranged for joint operation substantially as herein specified.

In testimony that I claim the invention above set forth I affix my signature in presence of two witnesses.

WILLIAM MORTIMER CLARK.
